UNITED STATES PATENT OFFICE.

ANTHONY J. SCHROEDER, OF DONALDSONVILLE, LOUISIANA.

BELLOWS ATTACHMENT FOR CHAIRS.

1,109,473.

Specification of Letters Patent.

Patented Sept. 1, 1914.

Application filed July 28, 1913. Serial No. 781,682.

To all whom it may concern:

Be it known that I, ANTHONY J. SCHROEDER, a citizen of the United States, residing at Donaldsonville, in the parish of Ascension and State of Louisiana, have invented certain new and useful Improvements in Bellows Attachments for Chairs; and I do hereby declare the following to be a full, clear, and exact description of the invention, such as will enable others skilled in the art to which it appertains to make and use the same.

The present invention relates to an improved power transmitting mechanism, and it consists in the constructions, combinations and arrangements herein described and claimed.

The purpose of the invention is to provide an improved power transmitting mechanism particularly adapted for use in connection with rocking chairs, whereby the rocking motion is utilized for causing a continuous draft of air for cooling the occupant of the chair.

A further purpose of the invention is to provide an apparatus of the type in question, which may be readily attached to any rocking chair and which will work without noise when in operation, and which is actuated wholly by the normal rocking motion of the chair.

The invention as designed is an improvement over the apparatus disclosed in my co-pending application for U. S. Patent, Serial No. 720,037, filed September 12, 1912.

In the accompanying drawings forming a part of this application, and in which similar reference symbols indicate corresponding parts in the several views: Figure 1 is a side elevation showing a rocking chair equipped with the present invention, and in one position of operation; Fig. 2 is a similar view showing the same in a different position; Fig. 3 is a front elevational view thereof; Fig. 4 is a side elevational view showing a modified construction of apparatus; Fig. 5 is a detail view showing one of the securing devices; and Fig. 6 is a detail view showing the bellows actuating means illustrated in Fig. 4.

Referring to the construction in further detail, 1 designates an ordinary rocking chair having secured on the under side of the seat 2 thereof a bellows 3 of any appropriate type. The securing means consists

of a strip 4 connected to one side of the bellows and having a looped end 5 designed to engage and grip the front edge of the seat 2 in substantially the manner shown. The bellows 3 is adapted to be actuated by the rocking motion of the chair through the medium of a device which has constant engagement with the chair supporting surface. Said device comprises a strip 6 having a leg 7 secured thereto, and fitted with a roller 8 which is held normally in engagement with the ground, or floor, by a weight 9 mounted on the leg 7. A bracing bar 10 connects the leg 7 with the strip 6, and serves as a connecting member for the operating mechanism of the second bellows, as will be presently explained. The second bellows 11 is secured to the back 12 of the rocker through the medium of the strip 13 having a hooked end 14 that fits over the head of the back 12 as in the manner shown. The strip 13 is hingedly connected at 15 to the strip 4, and thus provides a connected supporting means for the two bellows, which may be readily fitted to, or taken from the chair. The hooked end 14 of the strip 13 (see Fig. 5) provides the means for fitting the device to a chair, or removing same therefrom, and to which end said strip 13 has its upper end 16 constructed to provide a recess for receiving the spring 17 which engages with the end or head 18 of the hooked member 14 and holds the same under tension and in engagement with the back 12 of the chair.

In fitting the apparatus to the chair, the hook 5 is first placed to engage with the chair seat and the strip 13 then brought against the back of the chair, when the hook 14 may be withdrawn and sprung into position, as will be understood.

The means for actuating the second bellows 11 consists of a bell-crank lever 19, having one arm 20 connecting with the bar 21 that in turn connects the leg bracing member 10, and the other arm 22 engages with the bar 23 that is pivotally connected to the arm 24, secured to the back 25 of the bellows 11. Air is conducted from the bellows 3 and discharged at any convenient point in front of the occupant of the chair by a tube or pipe 26, which passes through the chair seat 2, as in the manner indicated in Figs. 1 and 3. In like manner, air is conducted from the bellows 11 by means of a

pipe 27 passing through the back of the chair and terminating at any convenient position adjacent the chair arm 28.

In the modified construction shown in Fig. 4, the arrangement is similar to that above described, except that the operative means for the second bellows consists of a curved arm 29 formed continuously with a strip 30 secured to the under side of the bellows 3. The free end of the curved arm 29 is provided with a roller 31, designed to work within a track provided by the box or casting 32, having a slotted opening 33 through which said arm 29 passes. Said box 32 is rigidly secured to the back 34 of the bellows 11, as clearly illustrated in Fig. 4.

In the normal rocking motion of the chair, the bellows 3 is operated through the medium of the leg 7 and roller 8 as the chair rocks forward, and through the connecting mechanism the bellows 11 is expanded. The backward rocking motion of the chair causes the bellows 3 to be expanded and the bellows 11 to be collapsed, due to the weight 9 holding the leg 7 constantly in engagement with the floor, or other surface, as illustrated in Figs. 2 and 4.

I have illustrated and described preferred and satisfactory constructions, but changes could be made within the spirit and scope of my invention.

I claim:

1. The combination with a rocker having

a seat and a back of an apparatus associated therewith, comprising a pair of hingedly-connected strips adapted to detachably engage with said seat and back, a bellows secured to the strip on said seat, a second bellows secured to the strip on said back, means for effecting the operation of the first-named bellows, operative connections between said means and the second-named bellows, and means for conducting air from said bellows.

2. The combination with a rocker having a seat and a back of an apparatus associated therewith, comprising a pair of hingedly-connected strips, one of said strips having a hooked end adapted to engage with the seat, and the other of said strips having a resiliently-connected hooked end adapted to engage with said back, a bellows secured to the strip on the seat, a second bellows secured to the strip on the back, a device carried by the first-named bellows adapted to effect the working thereof through the rocking motion of the chair, operative connections between said device and the second-named bellows, and means for conducting air from said bellows.

In testimony whereof, I affix my signature, in presence of two witnesses.

ANTHONY J. SCHROEDER.
